ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPE-WRITING MACHINE.

1,121,638.

Specification of Letters Patent.

Patented Dec. 22, 1914.

Application filed April 26, 1912. Serial No. 693,281.

To all whom it may concern:

Be it known that I, ALFRED G. F. KUROWSKI, a citizen of the United States, residing in Brooklyn borough, in the county of Kings and State of New York, have invented certain new and useful Improvements in Type-Writing Machines, of which the following is a specification:

This invention relates to means for enabling work-sheets, especially when small, such as labels, to be easily and securely held in position to be written on, and is particularly adapted to control such when they are stiff or when it is desired to write on the very margin.

As herein disclosed, the work-pieces are arranged to be held against the platen by a belt which extends from a fixed framework on the carriage down toward the platen. Said belt preferably terminates within the platen and is arranged to be kept under a continual tension as the platen may turn. Preferably, the belt is a resilient metal strip, one end of which is coiled and is fast on the framework. This coil may be gradually pulled out as the platen is turned in feeding the work-piece. The end of the belt in the platen preferably terminates in a hook portion, entering a radial slot in the platen, so that the belt will not jar out of place during the writing.

Other features and advantages will hereinafter appear.

In the accompanying drawings, Figure 1 represents a front view of so much of the carriage of an Underwood typewriting machine as is necessary to show my invention. Fig. 2 is an end view of the same partly in section. Fig. 3 is a section of a part showing the coils of the resilient belt. Figs. 4 and 5 are fragmentary views respectively of the supporting bar for the belt coils, and a bracket to which said bar is attached.

A platen 1 is mounted on a shaft 2 journaled in end pieces 3 and 4 of a platen frame. A work-sheet 5 may be held against said platen 1 by means of belts 6. These belts, which engage the platen by means of hooks or bent portions 7, extend from a cross-bar 8 of a framework fixed on said platen frame forward to the platen normally on a tangent thereto, near the printing line.

The work-sheet 5 may be inserted in front of the platen with its margins behind these

belts, so that its lower edge contacts with the bent portions of said belts, and is thereby alined. The platen is then turned and adjusted until the desired place on the card is brought opposite the printing point 63 whereupon the operator proceeds as usual, a line spacing mechanism, not shown, being supplied. The feed may be effected by turning the hand wheel 9, if desired, and the line spacing mechanism dispensed with. By 65 providing for the insertion of the card at the front of the machine the card is always in sight of the operator, and with a little practice the operator becomes very dexterous and sure in inserting the cards and 70 turning the platen to the right extent. In many instances it is not necessary to insert the card far—the printing point being toward the bottom of the card. The upper part of the card (see Fig. 2) does not then 75 become bent and the straightening or flattening of the cards is prompt and easy since the card is not carried around the platen. Another thing that helps in this connection is carrying the belt from the face of the 80 platen upward in a line practically tangent to the face of the platen near the printing point. The card is thus in contact with the platen to the least degree of arc practicable.

The platen may be arrested at the proper 85 point for inserting the paper, by means of a stop 10, which co-operates with a stop 11 on the end piece 4; and these stops will prevent the platen from being turned more than a full revolution, thus making it im- 90 possible to unduly wind up the belts 6.

Each belt 6 comprises a coil portion 15 lying within a barrel 14, which coil is arranged to be drawn out as the platen is rotated backwardly, and the end of each coil 95 is fast to a pin 16 in its barrel, so that when the platen is turned forwardly, the coil which is tensioned and set, will tend to pull back the straight part of the belt with the returning platen. Thus constructed the 100 coiled end of each belt acts as a spring of even and uniform tension and the belt as a whole, is resilient and self-tensioning and the tension effect is uniform practically throughout the turning of the platen. The 105 spring and belt being all one, moreover, all but two fastenings are dispensed with, and these are simple and positive, so that there is nothing to get out of order, become detached, or rattle and jar the machine.

The cross-bar 8, by which the free ends of the belts are supported, comprises a spline 12, in which a key 13 in a barrel 14 slides, and holds said barrel against rotation.

The cross-bar 8 is prevented from turning by means of a tongue 17, which enters a flat-sided opening 18 in one of the supporting arms 19, rising from the end pieces 3 and 4 of the platen frame. As the belt carrying members slide across the cross-bar 8 to adjust the belts 6 to any desired work-sheet, the hook ends 7 of the belts slide in a slot 21 in a metal insert 22 in the platen. The belt carrying members 14 may be set on cross-bar 8 at any desired position by means of set screws 20 in the hubs thereof.

Variations may be resorted within the scope of the invention, and portions of the improvements may be used without others.

Having thus described my invention, I claim:

1. In a typewriting machine, the combination of a rotatable platen, and a metallic self-tensioning band attached to said platen and arranged to hug a work-sheet against the platen.

2. In a typewriting machine, the combination of a rotatable platen, and a metallic band attached to said platen and adapted to hold a work-sheet against said platen, said band having an integral extension forming resilient means for maintaining tension on said band.

3. In a typewriting machine, the combination with a rotatable platen, and a platen frame in which it is journaled, of means for slidably attaching a band to said platen for adjustment longitudinally of the platen, a framework on said frame, a fixed member on said framework on which a band holding member is slidably mounted, and a band extending from said holding member to said platen.

4. In a typewriting machine, the combination with a rotatable platen, and a platen frame in which it is journaled, of means for slidably attaching a band to said platen, a framework on said frame, a fixed member on said framework on which a band holding member is slidably mounted, a band extending from said holding member to said platen, and arranged to tend to rotate the platen, and a stop for arresting said platen.

5. In a typewriting machine, the combination with a rotatable platen, and a platen frame in which it is journaled, of a resilient metal band adapted to hold a work-sheet against said platen, said band comprising a spirally coiled portion which is fast to a fixed member on said frame, and which forms a resilient means to maintain tension on the band.

6. In a typewriting machine, the combination with a rotatable platen and a platen

frame in which it is journaled, of a framework on said frame, a cross-bar on said framework, a belt holder splined to slide on said shaft, a resilient belt comprising a coiled portion arranged within said holder and a reach extending to said platen, and means on said platen to hold said belt.

7. In a typewriting machine, the combination with a rotatable platen, and a platen frame in which it is journaled, of a framework on said frame extending the length of the platen, a belt holder splined to slide on said framework substantially the length of the platen, a resilient belt extending from said holder to the platen, and means to attach said belt to the platen.

8. In a typewriting machine, the combination with a rotatable platen and a platen frame in which it is journaled, of means for attaching a band to said platen, a framework on said frame, and a band attached to said platen and having an integral resilient extension connected to the framework tending to coil and thereby maintaining tension on the band.

9. In a typewriting machine, the combination of a rotatable platen, bands attached thereto and adapted to hold a work-sheet against the platen, and means forming a part of each band for independently maintaining tension on said bands.

10. In a typewriting machine, the combination of a rotatable platen, resilient bands attachable to the platen and adjustable longitudinally thereof, and means for holding the bands in adjusted position tending to coil.

11. In a typewriting machine, the combination of a rotatable platen, bands attachable thereto and adapted to hold a work-sheet against the platen, said bands being adjustable longitudinally of the platen and extending in a straight line from the platen, and means for adjustably supporting the extended portions of the bands.

12. In a typewriting machine, the combination of a rotary platen, resilient self-tensioning non-extensible bands attachable at one end thereto and relatively adjustable in the direction of the platen axis, and means for supporting the other ends of said bands above the platen.

13. In a front-strike typewriting machine, the combination of a rotary platen, a non-extensible work-holding resilient self-tensioning band, extending upward from the platen, and adapted to turn the platen, and means above the platen for supporting the upper end of the band.

14. In a typewriting machine, the combination of a rotary platen, a self-tensioning non-extensible work-holding band attached at one end to the platen and normally extending across the printing line and at a tangent to the platen at a point

adjacent the printing line, and means to support the extended portion of the said band.

15. In a typewriting machine, the combination of a rotary platen, of resilient self-tensioning non-extensible work-holding bands connected thereto and extending in a direction to permit work-pieces to be fed between said band and the periphery of the platen, the tension and resiliency of the bands tending to rotate the platen in a forward direction.

16. In a typewriting machine, the combination of a rotary platen, coöoperating stops to limit the rotation of the platen in both directions, resilient work-holding bands each attached at one end to the periphery of the platen and extending in a line from the platen, and locking means for supporting the other ends of said bands and maintaining the bands under tension.

17. In a typewriting machine, the combination of a rotary platen, stops to limit the rotation of the platen in either direction, and resilient work-holding bands connected to the peripheral surface of the platen substantially at the printing line when the platen is at the limit of its rotation in one direction, said bands extending substantially at a tangent to the platen from the point of connection when the platen is in such position.

18. In a typewriting machine, the com-

bination of a rotary platen, a strip of resilient sheet metal having a portion wound and set to form a coil spring and an extended straight portion, said straight portion being connected to the platen and forming a work-holding band, and a support for said coil spring.

19. In a typewriting machine, the combination of a rotary platen, a strip of elastic sheet metal having a portion wound and set to form a coil spring and an extended straight portion, said straight portion being connected to the platen and forming a work-holding band, and a support for said coil spring on which the latter is adjustable in the direction of the platen axis, said connection between the platen and band also permitting adjustment of the latter along the platen.

20. In a typewriting machine, the combination with a rotary platen and a platen frame, of a framework mounted on said frame and comprising a bar parallel with the platen, barrels adjustable along said bar, springs mounted on said bar in said barrels, bands extending from said springs to the platen, said bands being continuations of the springs and means for adjustably connecting said bands to the platen.

DISCLAIMER.

1,121,638.—*Alfred G. F. Kurovski*, Brooklyn, N. Y. TYPEWRITING MACHINE.

Patent dated December 22, 1914. Disclaimer filed October 21, 1922, by the assignee, *Underwood Typewriter Company*.

Hereby enters this disclaimer, to wit:

As to claim 11 of said Letters Patent, any construction thereof, or employment as part of the subject-matter thereof, wherein or whereby the bands, referred to in said claim, either;—are not adjustable longitudinally of the platen, while attached thereto; or—are not connected directly to the peripheral surface of the platen within the purport of the decision of the Law Examiner of the United States Patent Office, rendered July 21, 1915, in a patent interference proceeding, No. 38,484, entitled "Kurovski v. Steele."
